UNITED STATES PATENT OFFICE.

CHARLES W. HOEHN, OF BLOOMINGTON, ILLINOIS.

SOLDERING-LAMP.

SPECIFICATION forming part of Letters Patent No. 269,415, dated December 19, 1882.

Application filed October 18, 1882. (No model.)

To all whom it may concern:

Be it known that I, CHARLES W. HOEHN, of Bloomington, in the county of McLean and State of Illinois, have invented a new and Improved Soldering-Lamp, of which the following is a full, clear, and exact description.

The object of my invention is to furnish a lamp for the use of jewelers, dentists, and others in the work of soldering, and conveniently adapted for all varieties of such work.

The invention consists in a laterally-adjustable wick-tube, by which the flame is brought to any desired point.

Reference is to be had to the accompanying drawings, forming a part of this specification, in which similar letters of reference indicate corresponding parts in all the figures.

Figure 1 is a side elevation of my improved lamp. Fig. 2 is a vertical section of the same. Fig. 3 is a detail section of the wick-tube joint on the line *x x*, Fig. 2.

The body *A* of the lamp may be constructed of any suitable size, form, and material, and is provided with a collar, *a*, that receives the movable cap *b*, carrying the wick-tube *B*.

The cap *b* is provided with fixed flanges *c c*, of circular form, and to the lower end of the wick-tube *B* is attached a circular band, *d*, which passes between the flanges *c* of the cap; and the edges of the flanges *c* being bent over the edges of the band, the wick-tube is thereby held in place, and is free to be turned on a horizontal axis at one side or the other, as illustrated by dotted lines in Fig. 1, and full lines in Fig. 3. The under side of the band is apertured to allow the wick to pass through. By this construction the tube can be turned to bring the flame in any desired position, and more or less closely to the work that is being soldered.

Upon the wick-tube *B* is a loose sleeve, *f*, the side of which is slotted for engagement with the pin *g*, in the manner of a bayonet-joint, so that the sleeve can be raised and lowered and held in any position as adjusted. When raised the end of the sleeve projects above the end of the wick-tube, thereby inclosing more or less wick and regulating the flame.

h is a cap of a size for passing freely over the wick-tube and the movable cap *b* of the lamp, which latter is formed with a flange, *i*, upon which the bottom of the cap *h* rests. This is to be put in place when the lamp is not in use, and, as it covers the entire tube and fits snugly at the bottom, prevents the evaporation of the liquid employed in the lamp.

This lamp is especially adapted for the use of jewelers, dentists, and others who do considerable small work requiring accurate regulation of the flame in its position with reference to the lamp.

I am aware that it is old to support the oil-vessel of the lamp so as to be laterally adjustable.

Having thus described my invention, I claim as new and desire to secure by Letters Patent—

1. In soldering-lamps, the laterally-adjustable wick-tube *B*, substantially as shown and described.

2. In lamps, the combination of the cap *b*, provided with flanges *c c*, and the wick-tube *B*, formed with the band *d*, combined, substantially as shown and described, to allow adjustment of the wick-tube to either side, as set forth.

CHARLES WASHINGTON HOEHN.
